UNITED STATES PATENT OFFICE

2,420,889

CIRCUIT INTERRUPTER

Winthrop M. Leeds, Pittsburgh, Pa., assignor to
Westinghouse Electric Corporation, East Pitts-
burgh, Pa., a corporation of Pennsylvania

Application April 6, 1945, Serial No. 586,989

10 Claims. (Cl. 200—150)

1

This invention relates to circuit interrupters in general, and more particularly to circuit interrupters of the liquid-break type.

In a patent application filed April 3, 1945, Serial No. 586,354, by Winthrop M. Leeds and James M. Cumming, and assigned to the assignee of the instant application, there is disclosed and claimed a novel type of circuit interrupter utilizing first and second piston means, in which the first piston means forces fluid through a suitable interrupting structure against an interrupting arc, and the second piston means is operated by the pressure set up by a serially related pressure-generating arc. It is an object of my invention to improve the interrupting structures set forth in the aforesaid application.

Another object is to provide an improved circuit interrupter of the type drawing both a pressure-generating arc and an interrupting arc. I provide a first piston member movable in the interrupting chamber and a second piston member movable in the pressure-generating chamber with suitable connecting means for causing the simultaneous operation of both piston members.

Another object is to provide an improved circuit interrupter, in which an improved contact-mounting arrangement is employed, whereby at least one of the contacts moves within a dashpot.

Further objects and advantages will readily become apparent upon a reading of the following specification, taken in conjunction with the drawing, in which:

Figure 1 is an elevational view, partly in section, of a circuit interrupter embodying my invention;

Fig. 2 is an enlarged vertical sectional view through the right-hand arc-extinguishing unit of Fig. 1, the parts being shown in the partly open circuit position;

Fig. 3 is a view similar to Fig. 2, but showing the disposition of the parts in the fully closed circuit position of the interrupter;

Fig. 4 is a sectional view, taken along the line IV—IV of Fig. 2; and

Fig. 5 is a sectional view, taken along the line V—V of Fig. 2.

Referring to the drawing, and more particularly to Figure 1 thereof, the reference numeral 1 designates a tank, in which a suitable arc-extinguishing fluid 2, in this instance circuit-breaker oil, is contained, filling the tank 1 to the level 3. The tank 1 has a cover 4 from which depend two insulating terminal bushings 5, through which extend terminal studs (not shown).

2

Threadedly secured to the lower ends of the terminal studs are contact feet 6 which support identical arc-extinguishing units, generally designated by the reference numeral 7.

5 Reciprocally operable in a vertical direction within the tank 1 is an insulating operating rod 8, to the lower end of which is secured a conducting bridging member 9 which serves, in the closed circuit position of the interrupter as shown in the full lines of Fig. 1, to electrically interconnect the two arc-extinguishing units 7.

The unit 7 comprises an insulating casing 10 in which is disposed an insulating plate 11 rigidly secured in place by screws 12 to form a pressure-generating chamber generally designated by the reference numeral 13 and an interrupting chamber generally designated by the reference numeral 14. A first piston member 15, having formed therein an orifice 16, moves within the 15 interrupting chamber 14 being guided by the inner walls of the insulating casing 10. A second piston member 17 of annular configuration moves within the pressure-generating chamber 13. Insulating rods 18 interconnect the first and 20 second piston members to cause their simultaneous operation. The upper ends of the rods 18 are threadedly secured to the piston 17. The lower portion of rods 18 are fixedly secured to piston 15 by pins 18a.

25 30 The orifice construction 16 preferably follows the teachings set forth and claimed in U. S. patent application filed March 23, 1945, Serial No. 584,413 by Thomas E. Browne, Jr., and assigned to the assignee of the instant application.

35 A slide valve 19 moves within the pressure-generating chamber 13 to control venting means provided at both ends of the pressure-generating chamber 13 in the form of vents 20 and vents 21. The slide valve 19 has integrally formed thereon flanges 22, 23 so that the second piston member 17 may effect the operation thereof. The contact foot 6 supports, in a resilient manner, a relatively stationary contact 24, suitable conductors 25 being provided to electrically interconnect the stationary contact 24 with the contact foot 6, which in this instance serves as a top cover for the casing 10.

40 An intermediate contact 26 is provided having a flange portion 27 which moves within a dashpot 50 generally designated by the reference numeral 28 and formed by an insulating cylinder 29 secured in place to the insulating plate 11 in any suitable manner. Check valves 30 may be provided for the pressure-generating chamber 13 to close during high-pressure conditions therein and to open

during low-pressure conditions following a circuit interrupter opening operation. A compression spring 31 disposed between the plate 11 and a flange 32 integrally formed with the intermediate contact 26 serves to bias the intermediate contact 26 downwardly.

The intermediate contact 26, in the closed circuit position of the interrupter as shown in Fig. 3, engages with a lower movable contact 33, the latter being mechanically supported by a lost-motion connection 34 to a spider member 35 in which are threadedly secured the rods 18. The lower movable contact 33 has an extension 36 which is slidably guided through an aperture 37 provided at the bottom of the casing 10 and is engaged by the conducting cross bar 9 in the usual manner.

The lost-motion connection 34 comprises a compression spring 38 disposed between the spider member 35 and a flange 39 integrally formed with the extension 36 of the movable contact 33. A flange 40 is integrally formed with the movable contact 33 and serves to limit the downward motion thereof with respect to the spider member 35. Check valves 41 may be provided for the region 42 below the first piston member 15 in the interrupting chamber 14.

The operation of the unit 7 will now be explained. In the closed circuit position, as shown in Figs. 1 and 3, the electrical circuit therethrough comprises contact foot 6, conductors 25, stationary contact 24, intermediate contact 26, lower movable contact 33, through the conducting bridging member 9 and through the left-hand arc-extinguishing unit 7 in an identical manner. Upon the downward movement of conducting bridging member 9, the compression spring 36 causes a downward movement of the lower movable contact 33 with respect to the spider member 35 thus unplugging the orifice 16. The accelerating compression spring 43 causes downward travel of both the first and second piston members 15, 17, they being interconnected by the rods 18. The downward movement of the first piston member 15 forces oil from the region 42 through the orifice 16 adjacent the interrupting arc 44 drawn between the contacts 26, 33. The oil may then pass out of the interrupting chamber 14 through the vents 45 provided in the wall of the casing 10. During this movement, the check valves 41 remain closed. The provision of the dashpot 28 in which the intermediate contact 26 moves causes a separation between the contacts 24, 26, after the separation between the contacts 26, 33. This establishes a pressure-generating arc 46 which establishes pressure within the pressure-generating chamber 13.

During the interruption of high currents, the pressure created at the pressure-generating arc 46 within the pressure-generating chamber 13 drives the second piston member 17 downwardly to assist the accelerating compression spring 43 in forcing the first piston member 15 to provide a greater quantity of oil passing through the orifice 16 at increased velocity to interrupt the larger arc with greater gas formation which is formed between the contacts 26, 33.

Interruption soon follows and the continued downward movement of the first piston member 15 provides a flushing flow of oil through the orifice 16 and out the vents 45. At the extreme end of the opening travel of the second piston member 17, the slide valve 19 closes the vents 21 and opens the vents 20, thereby permitting accumulated gas and contaminated oil to pass out of the pressure-generating chamber 13 through the

vents 20. Upon the subsidence of pressure within the pressure-generating chamber 13, the check valves 30 open and fresh oil may flow into the chamber 13. The bridging member 9 may separate from the extension 36 of the lower movable contact 33 to introduce an isolating gap in the circuit.

During the closing operation, the bridging member 9 moves upwardly to pick up extension 36, and moves the contact 33 upwardly with respect to the spider 35 by virtue of the lost-motion connection 34, to plug the orifice 16 and raise both the first and second piston members 15, 17 upwardly charging the accelerating compression spring 43. During this movement, oil is drawn in through the check valves 41 to thereby provide a fresh quantity of clean oil in the region 42 below the first piston member 15. Also, the upward movement of the second piston member 17 forces contaminated oil out of the pressure-generating chamber 13 through the vents 20. During this operation, the movable contact 33 strikes the intermediate contact 26 and raises the latter to effect an engagement between the contacts 24, 26 to effect a closing of the electrical circuit through the interrupter. At the extreme upward end of the travel of the second piston member 17, the piston member 17 engages the flange 22 to raise the slide valve 19 to cause closing of the vents 20 and opening of the vents 21. The unit 7 is then in readiness for the next opening operation.

During the interruption of low currents, where the pressure established at the pressure-generating arc 46 is not appreciable, reliance may be had upon the accelerating compression spring 43 to cause the necessary downward movement of the first piston member 15 to cause interruption of the interrupting arc 44.

The foregoing description discloses how I have solved the problem of increasing the mechanical driving power for the fluid moving piston 15 as the arc current is increased, the additional piston driving effort being derived from a serially-related pressure-generating arc 46. One of the most important novel features of the unit 7 is the valve arrangement which permits dirty oil to be flushed out and clean oil brought into both the interrupting chamber 14 and the pressure-generating chamber 13. The pressure produced at the pressure-generating arc 46 during high-current interruption is particularly effective during high currents in speeding up the motion of the lower piston and thus increasing the oil flow velocity in the orifice 16 so as to sweep away the larger volumes of gas which are formed.

It is to be observed that opening the breaker on no-load operation, that is, with no current passing through the breaker, permits the annular piston 17 to draw clean oil into the pressure-generating chamber 13 through the check valves 30. Also, it is to be noted that excessive pressure in the pressure-generating chamber 13 will act on the upper edge 47 of the cylindrical slide valve 19 so as to open the exhaust ports 20 for emergency-pressure relief.

From the foregoing description, it will be apparent that I have provided an interrupter of improved construction, in which novel valve means are employed to circulate oil through the interrupter. It will also be apparent that I have provided novel interconnecting means, interconnecting the first and second piston means, the second piston means being actuated by a serially-related pressure-generating arc.

Although I have shown and described a specific

structure, it is to be clearly understood that the same was merely for the purpose of illustration, and that changes and modifications may readily be made therein by those skilled in the art, without departing from the spirit and scope of the appended claims.

I claim as my invention:

1. In a circuit interrupter, means for establishing an interrupting arc, a first piston means for facilitating the extinction of the interrupting arc, means for establishing a pressure-generating arc, a second piston means operated by pressure from the pressure-generating arc to assist the motion of the first piston means, and means rigidly interconnecting the first and second piston means.

2. In a circuit interrupter, means for establishing an interrupting arc, a first piston means for facilitating the extinction of the interrupting arc, means defining an orifice carried by the first piston means, means for establishing a pressure-generating arc, a second piston means operated by pressure from the pressure-generating arc to assist the motion of the first piston means, and means rigidly inter-connecting the first and second piston means.

3. In a circuit interrupter, an arc-extinguishing unit, a first piston member movable within the unit, means biasing the first piston member to move to the open circuit position, a movable contact carried by the first piston member, a relatively stationary contact cooperable with an intermediate contact to establish a pressure-generating arc, the intermediate contact being cooperable with the movable contact to establish an interrupting arc, a second piston member operated by pressure created at the pressure-generating arc to assist the opening motion of the first piston member, and means rigidly inter-connecting the first and second piston members.

4. In a circuit interrupter, an arc-extinguishing unit, a first piston member movable within the unit, means biasing the first piston member to move to the open circuit position, a movable contact carried by the first piston member, a relatively stationary contact cooperable with an intermediate contact to establish a pressure-generating arc, the intermediate contact being cooperable with the movable contact to establish an interrupting arc, a second piston member operated by pressure created at the pressure-generating arc to assist the opening motion of the first piston member, venting means to relieve the pressure created at the pressure-generating arc operated by the opening motion of the second piston member, and means rigidly interconnecting the first and second piston members.

5. In a fluid circuit interrupter, an arc-extinguishing unit, the unit comprising a pressure-generating chamber and an interrupting chamber, means for establishing a pressure-generating arc within the pressure-generating chamber and an interrupting arc within the interrupting chamber, a first piston member movable in the interrupting chamber to force fluid toward the interrupting arc to facilitate its extinction, a second piston member movable in the pressure-generating chamber and responsive to the pressure within the pressure-generating chamber, and connecting means for causing the simultaneous operation of both piston members.

6. In a circuit interrupter, an arc-extinguishing unit, the unit comprising a pressure-generating chamber and an interrupting chamber, a first piston member movable in the interrupting chamber, a second piston member movable in the pressure-generating chamber, connecting means for causing the simultaneous operation of both piston members, a stationary contact disposed in the pressure-generating chamber, an intermediate contact extending into both chambers, and a movable contact carried by the first piston member.

7. In a circuit interrupter, an arc-extinguishing unit, the unit comprising a pressure-generating chamber and an interrupting chamber, a first piston member movable in the interrupting chamber, a second piston member movable in the pressure-generating chamber, connecting means for causing the simultaneous operation of both piston members, and means defining an orifice carried by the first piston member.

8. In a circuit interrupter, an arc-extinguishing unit, the unit comprising a pressure-generating chamber and an interrupting chamber, a first piston member movable in the interrupting chamber, a second piston member movable in the pressure-generating chamber, connecting means for causing the simultaneous operation of both piston members, means defining an orifice carried by the first piston member, and a movable contact carried by the first piston member by a lost-motion connection so as to plug the orifice during the closing operation.

9. In a circuit interrupter, an arc-extinguishing unit, the unit comprising a pressure-generating chamber and an interrupting chamber, a first piston member movable in the interrupting chamber, a second piston member movable in the pressure-generating chamber, connecting means for causing the simultaneous operation of both piston members, a stationary contact disposed in the pressure-generating chamber, an intermediate contact extending into both chambers, a movable contact carried by the first piston member, a dashpot, and the intermediate contact being movable in the dashpot.

10. In a circuit interrupter, an arc-extinguishing unit, the unit comprising a pressure-generating chamber and an interrupting chamber, a first piston member movable in the interrupting chamber, a second piston member movable in the pressure-generating chamber, connecting means for causing the simultaneous operation of both piston members, venting means at both ends of the pressure-generating chamber, and a slide valve for the venting means operable by opening and closing motion of the second piston member.
